Primary Examiner — Jack Reickel*Assistant Examiner* — Salamah Jordan(74) *Attorney, Agent, or Firm* — Lawrence B. Goodwin; Mandelbaum Barrett PC(57) **CLAIM**

The ornamental design for an exercise board, as shown and described.

DESCRIPTION

FIG. 1 is a top, right, front perspective view showing the exercise board;

FIG. 2 is a front view showing the exercise board;

FIG. 3 is a rear view showing the exercise board;

FIG. 4 is a left side view showing the exercise board;

FIG. 5 is a right side view showing the exercise board;

FIG. 6 is a top view showing the exercise board; and,

FIG. 7 is a bottom view showing the exercise board.

Where utilized, the broken lines show portions of the exercise board that form no part of the claimed design.
